UNITED STATES PATENT OFFICE.

SAIBEI KAKUDA, OF FUKUYAMA-SHI, JAPAN, ASSIGNOR TO SAIBI MOJIAMI KABUS-
HIKI KAISHA, OF FUKUYAMA-SHI, JAPAN, A CORPORATION OF JAPAN.

REED FOR NET-MAKING MACHINES.

Application filed March 28, 1927, Serial No. 179,102, and in Japan April 2, 1926.

This invention relates to improvements in reeds for net-making machines of the type in which the knotless netting fabric, such as may be used for fishing and other purposes, are made, and has for its object to provide a reed, simple in construction and efficient in operation, for converging the strands for the netting within limited small spaces in proper position for interlocking 10 operation.

The accompanying drawings illustrate a part of the net-making machine with the reed according to the invention applied thereto, and in which:—

15 Fig. 1 is a plan view, a portion of the reed being broken away, showing certain means for driving the reed.

Fig. 2 is a perspective view.

20 Fig. 3 is an enlarged detail view of the driving connection of the reed.

In order to insure a clear and accurate understanding of my reed and method of employing it, I will illustrate and describe an outline of the construction of a machine 25 of the type in which my reed is designed to be applied, by way of example. In Fig. 2, 1 is reciprocating plate and 2 is a stationary plate, which form an upper working platform. Directly below said upper 30 working platform is provided a lower working platform identical therewith, the reciprocating plate 6 of which is connected to the reciprocating plate 2, so as to be laterally reciprocated together. The construction of 35 the working platforms will be described herein merely of the upper working platform, as the lower working platform is substantially of the same construction. The working platform is formed with a series of 40 working grooves 3, which consists of three circular holes formed in series so as to somewhat overlap the adjacent hole, the intermediate hole being located to equally extend across the abutting edges of said plates, 45 and receives four working heads 7 of a cross section form of double convex lens in general outline for carrying the spools or strand carriers 8 and three cam rollers 4 having opposite concave surfaces *a* and convex surfaces *b* in general outline for effecting round motion of said working heads. Said cam roller is supported by a bar 5 extending down to the reciprocating plate 6 of the lower working platform. In order to permit lateral movement of the reciprocating

plate 1, the cam rollers in an intermediate row are made in two halves, instead of being formed in one piece. With the arrangement of the parts as described above, each pair of the strands upwardly extending 60 from the strand carriers 8 carried by the working heads 7 are intertwined by rotation of the side rollers 4 and consequent rounding motion of each pair of said working heads. Thus, after each pair of the strands has been intertwined through a certain length, all the working heads are stopped in the aligned position. Then each pair of the strands or the working heads in two rows at inner side are caused to cross 70 with each other by turning the intermediate rollers 180 degrees in a direction. Then the side rollers are turned 360 degrees in reverse direction and each pair of the strands is caused to intertwist one turn. Then the intermediate rollers are turned again 180 degrees in the same direction as before, and now the intertwisting operation for the strands is to be resumed. Thus the interlocking 75 operation for the strands is accomplished. The parts so far described, of course, form no part of the invention.

The reed embodying the invention is composed of two plate members 9 and 10, which are mounted on the overhead positions corresponding to the reciprocating plate 1 and stationary plate 2 respectively, substantially flush and in close contact edge to edge with each other, so as to be adapted to be moved by suitable means. The plate member 9 is 80 reciprocated through a length corresponding to one and a half central distance between adjacent working grooves, and the plate member 10 is reciprocated through a length corresponding to a half central distance between adjacent working grooves. The plate members 9 and 10 are provided with a series 85 of notches 11 and 12, regularly spaced along the abutting side edge thereof respectively, through which notches the strands pass. The notches 11 in the plate member 9 serve to shift the strands to the proper position for interlocking the strands by hooking the same in one of the ends thereof. The notches 12 in the plate member 10 serve to form 90 confined spaces for the strands upon the interlocking operation of the strands in co-operation with the notches 11, the same being moved in the contrary direction to the movement of the notches 11.

In operation, the plate member 9 moves to a direction through the aforesaid length, hooking the strands, while the plate member 10 moves to the opposite direction through the aforesaid length, and the both plates rest on the proper interlocking position as shown in Fig. 2, providing the spaces for the strands, so confined as to converge the same, during the interlocking operation.

10 The movement of the reed may be effected by any suitable means, and in Figs. 1 and 3 the means are illustrated by way of example, in which a lever 13 is pivoted on the machine frame 14 near its one end. To the 15 one end of the lever 13 near the pivot 14 the plate member 10 is connected through a connecting link 15, and to the other end the plate member 9 and an eccentric 16 mounted on a driving shaft 17 are connected through connecting links 18 and 19 respectively, the eccentric being adapted to be intermittently rotated by suitable means. With this construction, it will be seen that the plate members 9 and 10 may be moved intermittently

from the eccentric to set the strands of the 25 twines in the proper interlocking position and at the same time to provide the spaces for the strands, so confined as to converge the same, during the interlocking operation.

Having now particularly described and ascertained the nature of my said invention, and in what manner the same is to be performed, I declare that what I claim is:—

A reed for net-making machines for interlocked netting, which consists of two plate members having respectively a series of notches in a side edge thereof and which are adapted to be positioned substantially flush and in close contact with each other at the notched side edges and to be moved intermittently so as to shift the strands of the twines to the proper interlocking positions by the time of the commencement of the interlocking operation and to keep the strands confined in small spaces during the 45 said interlocking operation.

In testimony whereof I affix my signature.

SAIBEI KAKUDA.
